CONTAINERS FOR CABINETS

Pearl Joseph, Merton Grove, Ill.

Application March 21, 1958, Serial No. 722,908

7 Claims. (Cl. 312—249)

This invention relates generally to containers and more specifically to an improved refuse container and certain means for operatively mounting the container in a cabinet.

Refuse containers, as generally known, in the art, have a single function and in use are inconvenient and inefficient, especially when used in a kitchen.

The object of the present invention is to provide a refuse container construction wherein a single container will perform a plurality of different functions.

A further object of the present invention is to provide a refuse container which will efficiently perform a number of refuse storage functions and which may easily be formed as a one-piece container by simple molding processes.

Another object of the present invention is to provide a refuse container construction which is ideally adapted for use in a kitchen.

Another object of the present invention is to provide a certain molded refuse container which will perform a plurality of refuse storing functions and which is cooperable in a plurality of different ways with certain track means for a cabinet such as a kitchen sink cabinet.

Other objects and features of the present invention will be apparent upon a perusal of the following specifications and drawings of which:

Figure 1 is an isometric view of a refuse container constructed according to the present invention;

Figure 2 is a top plan view of the refuse container of Figure 1;

Figure 3 is a side elevational view of the container shown in Figure 2;

Figure 4 is a partial front elevational view of a kitchen sink cabinet having the container operatively mounted therein in one particular manner;

Figure 5 is a top plan view of another kitchen sink cabinet with the container operatively mounted therein in another particular manner;

Figure 6 is a partial isometric view of one of the tracks of the subject invention; and

Figure 7 is a partial cross-sectional view showing the cooperation between one of the tracks and one of the slide members molded on the container.

The present embodiments are the preferred embodiments but it is to be understood that changes can be made in the present embodiments by one skilled in the art without departing from the spirit and scope of the present invention.

For a detailed description of the present invention reference is made to the drawings. The container comprises a back wall 10, an integrally formed lower front and side walls 11 and an integrally formed upper front and side walls 12, a bottom wall 13, dividing walls 14, 15, 16, and 17, a pair of upper slide members 18, a pair of rear slide members 19, and a pair of lower slide members 20. The curved front and side walls 11 are substantially smaller in height than the curved front and side walls 12. The curved front and side walls 11 have a greater radius of curvature than the curved front and side walls 12 so

2

that a lower compartment is defined by portions of the back wall 10, the curved front and side walls 11, the curved front and side walls 12 and the bottom wall 13. This lower compartment is divided into separate compartments by the dividing walls 15, 16, and 17 which extend between the curved front and side walls 11 and the curved front and side walls 12. Although the dividing walls 15, 16 and 17 are shown as maintained by suitable vertical slots on the inner surface of the curved front and side walls 11 and the outer surface of the curved front and side walls 12, it is intended that these dividing walls may be integrally formed with the rest of the container.

The compartment formed by the curved front and side walls 12 and a portion of the back wall 10 vertically extends from the bottom wall 13 to a point substantially above the upper edge of the curved front and side walls 11. This compartment is divided into two separate compartments by the dividing wall 14. Although the dividing wall 14 is shown as mounted in suitable slots formed on the inner surface of the rear wall 10 and the inner surface of the curved front and side walls 12, it is intended that this dividing wall 14 may be integrally formed with the remainder of the container.

In use it is intended that suitable refuse bags such as paper grocery bags may be folded and stored in the compartments defined by the curved front and side walls 11. Two of these bags in an open condition are positioned within the compartments defined by the curved front and side walls 12 and one of these bags may be used for burnable refuse while the other is used for unburnable refuse. As the refuse bags are filled they may be either disposed of or temporarily stored in one or more of the compartments formed by the curved front and side walls 11 which do not contain folded bags stored therein.

The back wall 10 is provided with a pair of vertically extending integrally molded slides 19 which are positioned in a spaced-apart relationship to each other. The slides 19 are somewhat T-shaped as may be seen in Figure 7. It is intended that the slides 19 cooperate with a pair of tracks 21 such as shown in Figure 6 in a sliding relationship. The tracks 21 are formed of any material having suitable rigidity and are provided with an extending flange whereby the tracks 21 may be secured within a cabinet. Although the slides 19 are shown as somewhat T-shaped, it is intended that the slides 19 and the tracks 21 may be formed of any other suitable cooperating configurations whereby the slides 19 are prevented from any movement in the tracks 21 other than a sliding movement longitudinally of the tracks 21.

The slides 18 which are formed of a shape identical to the slides 19 are integrally molded in a parallel spaced-apart relationship to each other along the upper edge of the side walls of the curved front and side walls 12. The slides 20 are also identical in shape to slides 19 and are integrally molded in a spaced-apart relationship to each other to depend from the bottom wall 13.

With the above described container and tracks 21 different mounting arrangements may be used in different cabinet constructions such as the two kitchen sink cabinet constructions shown in Figures 4 and 5. As shown in Figure 4 the cabinet 22 is provided with a sink 23 having a drain pipe 24 at the bottom thereof. The sink portion of the cabinet 22 is closed by a suitable door 25 pivotally mounted thereon. The tracks 21 are secured to the inner surface of the door 25 in a parallel spaced-apart relationship. The slides 19 of the container are mounted in the tracks 21 so that the container is movable between the solid line and dotted line positions shown in Figure 4. Any suitable catches known in the art may be used for holding the container in either the raised or lowered positions. It thus may be seen that in the use

of the container, the door 25 may be pivoted to the open position and the container raised to the dotted line position. With the container in this position, burnable and unburnable refuse produced in the area of the sink cabinet may be stored in the bags carried in the previously described compartments of the container. The container may then be moved to the downward position and when the door 25 of the cabinet 22 is closed, the container will be projected into the cabinet 22 and under the sink 23 and the drain pipe 24.

In the arrangement shown in Figure 5, the cabinet 26 is provided with two horizontally spaced-apart sinks 27 and 28. A pair of doors 29 enclose the front portion of the cabinet 26. In this arrangement the tracks 21 are secured within the cabinet 26 immediately below the upper surface thereof. The container is slidably carried by the slides 18 positioned within the tracks 21. In use it is merely necessary to open the doors 29 of the cabinet 26 and slide the container therefrom an amount sufficient to permit refuse to be disposed therein. The container may then be slid within the cabinet 26 and the doors 29 closed.

Although not shown, it is further intended that the tracks 21 may be mounted on the upper surface of the base of a cabinet such as cabinet 26. When the tracks 21 are so mounted, the container is positioned so that the slides 20 engage the tracks 21 thereby permitting the container to be moved within and out of the cabinet.

From the foregoing it may be seen that although the subject invention is simple in construction it provides substantial utility over refuse containers presently known in the art and substantial efficiency in the storage of refuse in cabinets such as kitchen sink cabinets. The construction of the present invention further permits the molding thereof by the use of simple molding processes.

Having described the invention what is considered new and desired to be protected by Letters Patent is:

1. A container for the storage of different materials comprising an integrally molded back wall, a bottom wall, a first curved front and side walls, and a second curved front and side walls, said back wall and said first curved front and side walls extending upwardly from said bottom wall a certain distance thereabove, said second curved front and side walls having a radius of curvature greater than the radius of curvature of said first curved front and side walls and extending upwardly from said bottom wall a distance less than said certain distance, a pair of tracks mountable in a cabinet, three pairs of slides integrally molded on said container and having a shape for cooperation with said tracks in a longitudinal sliding relationship, one pair of said slides being molded on the upper marginal edges of the side wall portions of said first curved front and side walls, the second pair of said three pairs of slides being vertically molded in a spaced-apart relationship to each other on said back wall, the third pair of said slides being molded in a spaced-apart relationship to each other on said bottom wall to depend therefrom and extending from said back wall to the forward edge of said container, so that each of said pairs of slides are mountable on said tracks for sliding movement of said container relative to said tracks in three different mounting arrangements of said tracks in a cabinet.

2. A container for the storage of different materials comprising an integrally molded back wall, a bottom wall, a first curved front and side walls, a second curved front and side walls, and a plurality of dividing walls, said back wall and said first curved front and side walls extending upwardly from said bottom wall a certain distance thereabove, one of said dividing walls being positioned to divide the compartment formed by said back wall and said first curved front and side walls into two separate compartments, said second curved front and side walls having a radius of curvature substantially greater

than the radius of curvature of said first curved front and side walls and extending upwardly from said bottom wall a distance less than said certain distance, the remaining ones of said dividing walls being vertically positioned in the compartment formed by said first and second curved front and side walls to form a plurality of compartments therein, a pair of tracks mountable in a cabinet, three pairs of slides integrally molded on said container and having a shape for cooperation with said tracks in a longitudinal sliding relationship, one pair of said slides being molded on the upper marginal edges of the side wall portions of said first curved front and side walls, the second pair of said three pairs of slides being vertically molded in a spaced-apart relationship to each other on said back wall, the third pair of said slides being molded in a spaced-apart relationship to each other on said bottom wall to depend therefrom and extending from said back wall to the forward edge of said container, so that each of said pairs of slides are mountable on said tracks for sliding movement of said container relative to said tracks in three different mounting arrangements of said tracks in a cabinet.

3. A container for the storage of different materials comprising an integrally molded back wall, a bottom wall, a first curved front and side walls, a second curved front and side walls, and a dividing wall, said back wall and said first curved front and side walls extending upwardly from said bottom wall a certain distance thereabove, said dividing wall being vertically positioned in the compartment defined by said first curved front and side walls and said back wall to divide said compartments into two adjacent compartments, said second curved front and side walls having a radius of curvature substantially greater than the radius of curvature of said first curved front and side walls and extending upwardly from said bottom wall a distance less than said certain distance, a pair of tracks mountable in a cabinet, three pairs of slides integrally molded on said container and having a shape for cooperation with said tracks in a longitudinal sliding relationship, one pair of said slides being molded on the upper marginal edges of the side wall portions of said first curved front and side walls, the second pair of said three pairs of slides being vertically molded in a spaced-apart relationship to each other on said back wall, the third pair of said slides being molded in a spaced-apart relationship to each other on said bottom wall to depend therefrom and extending from said back wall to the forward edge of said container, so that each of said pairs of slides are mountable on said tracks for sliding movement of said container relative to said track in three different mounting arrangements of said tracks in a cabinet.

4. A container for the storage of different materials comprising an integrally molded back wall, a bottom wall, a first curved front and side walls, and a second curved front and side walls, said back wall and said first curved front and side walls extending upwardly from said bottom wall a certain distance thereabove, said second curved front and side walls having a radius of curvature substantially greater than the radius of curvature of said first curved front and side walls and extending upwardly from said bottom wall a distance less than said certain distance, a plurality of dividing walls, said back wall and said first curved front and side walls each having a vertical slot formed therein, one of said dividing walls being positioned in said slots to divide the compartment formed by said back wall and said first curved front and side walls into two adjacent compartments, the lower outer surface of said first curved front and side walls and the inner surface of said second curved front and side walls being formed to have a plurality of vertically disposed slots therein, the remainder of said plurality of dividing walls being positioned in different ones of said slots to divide the compartments formed by said first and second curved front and side walls into a plurality of adjacent compartments, a pair of tracks

mountable in a cabinet, three pairs of slides integrally molded on said container and having a shape for cooperation with said tracks in a longitudinal sliding relationship, one pair of said slides being molded on the upper marginal edges of the side wall portions of said first curved front and side walls, the second pair of said three pairs of slides being vertically molded in a spaced-apart relationship to each other on said back wall, the third pair of said slides being molded in a spaced-apart relationship to each other on said bottom wall to depend therefrom and extending from said back wall to the forward edge of said container, so that each of said pairs of slides are mountable on said tracks for sliding movement of said container relative to said tracks in three different mounting arrangements of said tracks in a cabinet.

5. A container for the storage of different materials comprising an integrally molded back wall, a bottom wall, a first curved front and side walls, and a second curved front and side walls, said back wall and said first curved front and side walls extending upwardly from said bottom wall a certain distance thereabove, said second curved front and side walls having a radius of curvature greater than the radius of curvature of said first curved front and side walls and extending upwardly from said bottom wall a distance less than said certain distance, a pair of tracks securable in a cabinet, a pair of slides integrally molded on said container and having a shape for cooperation with said tracks in a longitudinal sliding relationship, said pair of slides being molded on the upper marginal edges of the side wall portions of said first curved front and side walls, so that said tracks are securable in a cabinet with said slides mountable on said tracks for said sliding movement of said container relative to said tracks in a depending relationship therefrom in a cabinet.

6. A container for the storage of different materials comprising an integrally molded back wall, a bottom wall, a first curved front and side walls, and a second curved front and side walls, said back wall and said first curved front and side walls extending upwardly from said

bottom wall a certain distance thereabove, said second curved front and side walls having a radius of curvature greater than the radius of curvature of said first curved front and side walls and extending upwardly from said bottom wall a distance less than said certain distance, a pair of tracks securable in a cabinet, a pair of slides integrally molded on said container and having a shape for cooperation with said tracks in a longitudinal sliding relationship, said pair of slides being vertically molded in a spaced-apart relationship to each other on said back wall, so that said tracks are vertically securable in a cabinet with said slides mountable on said tracks for vertical sliding movement of said container in a cabinet.

7. A container for the storage of different materials comprising an integrally molded back wall, a bottom wall, a first curved front and side walls, and a second curved front and side walls, said back wall and said first curved front and side walls extending upwardly from said bottom wall a certain distance thereabove, said second curved front and side walls having a radius of curvature greater than the radius of curvature of said first curved front and side walls and extending upwardly from said bottom wall a distance less than said certain distance, a pair of tracks securable in a cabinet, a pair of slides integrally molded on said container and having a shape for cooperation with said tracks in a longitudinal sliding relationship, said pair of slides being molded in a spaced-apart relationship to each other on said bottom wall to depend therefrom and extending from said back wall to the forward edge of said container, so that said tracks are securable in a cabinet to extend in an upward direction with said slides mountable on said tracks for sliding movement of said container in a cabinet.
